PASTE TUBE CONTAINER AND DISPENSER

Anne E. White, Minneapolis, Minn.

Application March 10, 1937, Serial No. 130,039

6 Claims. (Cl. 221—60)

This invention relates to paste tube containers and dispensers of that general type which is adapted to be secured in a convenient position and so constructed that small amounts of paste 5 may be dispensed from the tube when needed.

It is a general object of my invention to provide a structure which will conveniently and effectively dispense paste from a tube held within the device and also provide an efficient means for 10 preventing air from hardening the paste remaining in the tube.

It is a further object of my invention to provide such a container and dispenser which will accommodate different sizes of tubes.

15 A still further object is to provide such a device which may be constructed at little expense and which may be operated with considerable ease.

These and other objects and advantages of the 20 invention will be more fully set forth in the following description made in connection with the accompanying drawing, in which like reference characters refer to similar parts throughout the several views, and in which:—

25 Fig. 1 is a front elevation showing my invention applied to a convenient supporting base;

Fig. 2 is a side elevation thereof;

Fig. 3 is a slightly enlarged view of the lower portion with certain of the parts in section; and

30 Fig. 4 is a bottom plan view.

Referring to the drawing in more detail, the container and dispenser includes a grill like casting formed in two sections, 5 and 6. As shown, these sections may be made of wire or a similar material with the joints either soldered or welded together. However, it may be formed of sheet 35 metal and stamped from a blank. These sections are secured at their lower ends to a dispensing head 7, the section 6 being rigidly secured to said head as at 8 and the section 5 being pivotally secured at 9, the two sections being spaced apart 40 as shown in Figs. 2, 3 and 4. The upper ends of the two sections are held against separation by a suitable spring clip 10.

45 Extending backwardly from the upper and lower portions of the rear section 6 are brackets 11 which are bent laterally intermediate of their ends and provided with hook-like eyelets 12. These eyelets are adapted to receive securing elements such as nails or screws which extend into the supporting base 13 to hold the entire device 50 in position. These brackets 11 are extended beyond the eyelets 12 and are bent forwardly at an angle to provide hooks 14 for supporting tooth brushes and similar articles.

The dispensing head 7 is provided with an internal thread 15 which tapers inwardly and downwardly as shown in Fig. 3 and communicates with a dispensing mouth 16. The tapering threads are provided to accommodate various sizes of externally threaded tube spouts, an example of which is shown at 17. The spouts of the tubes are generally formed of a relatively soft metal and the dispensing head 7 will be formed of a relatively hard metal. Thus, when 10 a tube is inserted into the head which has a spout whose size is within the limits defined by the greatest and least diameters of the internal threads on the head, said internal heads will grip the relatively soft threads on the tube spout and 15 firmly engage them when the tube is given a slight turning movement. The lower part of the dispensing head 7 is provided with a radially extending ear 18 which supports a pivot pin 19 extending through a portion of the closure cap 20. A resilient spring 21 has one end anchored in the 20 dispensing head 7 and is so formed and positioned that it will normally bear against the outer surface of the cap 20 and urge it upward against the dispensing head 7. A cork gasket 22 may be inserted within the cap 20 in a manner similar to 25 the cork within the cap of the ordinary paste tube.

The pivot pin 19 is extended laterally for a considerable distance as best shown in Figs. 1 30 and 4 and its ends are bent forwardly to provide levers 23. These levers are adapted to be engaged by the hand or finger of the hand of a person holding a tooth brush and desiring to secure a charge of paste from the tube 24.

A key 25 is provided for engaging the flattened closed end of the tube 24 through the medium of a slot in the shank of the key. The key is provided with a handle 26 and is formed similarly to the keys provided in numerous cases for opening certain types of canned materials.

When the container and dispenser has been applied to the wall or to any other suitable supporting base, a tube of paste is inserted into the holder formed by the two sections 5 and 6. The tube is given a slight twist to firmly engage its externally threaded spout with the internal threads in the dispensing head 7. The key 25 is then placed over the end of the tube as shown in Figs. 1 and 2 and the pivotally mounted section 5 is swung into the position shown in the drawing with the spring clip 10 in engagement with the stationary section 6. If the material within the tube is tooth paste, a person desiring some of the paste will then grasp a tooth brush 55

in one hand and with the same hand depress one of the levers 23 causing the cap 20 to swing downwardly in open position and then with a slight movement of the same hand the brush head can be positioned beneath the dispensing opening 16 in the dispensing head. With the other hand the key 25 is turned to cause a squeezing action against the material within the tube since all tubes of this type are made from a ductile material and may easily be rolled from their closed end to force paste out of the open end.

As is clearly shown in the drawing, the relative positioning of the sections 5 and 6 of the container provides a keyway through which the key is adapted to move as paste is gradually forced from the tube and the closed end of the paste tube is rolled.

It will therefore be seen that I have provided a container and dispenser for paste tubes which is of extremely simple construction and can be manufactured for relatively little cost, but is, at the same time, readily adaptable to various sizes of paste tubes within certain limits without any change in the size of the container and dispenser or any parts thereof. It takes up no appreciable space in the bath room and is provided with hooks upon which tooth brushes may be placed when not in use. Because of the provision of these hooks, the device may be substituted for racks or hook arrangements which are often used for holding tooth brushes and at the same time acting as a container and dispenser for tooth paste.

It will, of course, be understood that various changes may be made in the form, details, arrangement and proportions of the various parts without departing from the scope of my invention which, generally stated, consists in the matter shown and described and set forth in the appended claims.

What is claimed is:—

1. In a paste tube container and dispenser, a dispensing head, a pair of complementary tube-receiving sections, one of said sections being rigidly connected to said head and the other of said sections being hingedly supported by said head and spaced from said first mentioned section to provide a keyway between said sections substantially throughout their length.

2. In a paste tube container and dispenser, a dispensing head, a pair of complementary tube-receiving sections, one of said sections being rigidly connected to said head and the other of said sections being hingedly supported by said head and spaced from said first mentioned sec-

tion to provide a keyway between said sections substantially throughout their length, and a key adapted to engage the closed end of a paste tube and also adapted to move in said keyway.

3. In a paste tube container and dispenser, a dispensing head, a pair of complementary tube-receiving sections, one of said sections being rigidly connected to said head and the other of said sections being hingedly supported by said head and spaced from said first mentioned section to provide a keyway between said sections substantially throughout their length, said dispensing head being provided with internal threads tapering inwardly and downwardly.

4. In a paste tube container and dispenser, a dispensing head, a pair of complementary tube-receiving sections, one of said sections being rigidly connected to said head and the other of said sections being hingedly supported by said head and spaced from said first mentioned section to provide a keyway between said sections substantially throughout their length, said dispensing head being provided with a discharge opening and with internal threads tapering inwardly and downwardly to communicate with said opening.

5. In a paste tube container and dispenser, a dispensing head, a pair of complementary tube-receiving sections, one of said sections being rigidly connected to said head and the other of said sections being hingedly supported to said head and spaced from said first mentioned section to provide a keyway between said sections substantially throughout their length, said dispensing head being provided with a discharge opening to receive the spout of a paste tube, a cap pivotally connected to said head and spring means for normally holding said cap against said head.

6. In a paste tube container and dispenser, a dispensing head, a pair of complementary tube-receiving sections, one of said sections being rigidly connected to said head and the other of said sections being hingedly supported by said head and spaced from said first mentioned section to provide a keyway between said sections substantially throughout their length, said dispensing head being provided with a discharge opening to receive the spout of a paste tube, and a cap pivotally connected to said dispensing head, said pivotal connection including a pivot pin extending through a portion of said head and rigidly secured to said cap, said pivot pin being extended laterally beyond said cap and said head and being bent to form an operating lever for said cap.

ANNE E. WHITE.
